(57) **CLAIM**

The ornamental design for a rail car power connector, as shown and described.

DESCRIPTION

FIG. 1 is a rear perspective view of a rail car power connector showing my new design;

FIG. 2 is a front perspective view thereof;

FIG. 3 is a front view thereof;

FIG. 4 is a rear view thereof;

FIG. 5 is a top view thereof;

FIG. 6 is a bottom view thereof;

FIG. 7 is a right view thereof; and,

FIG. 8 is a left view thereof.

In the drawing views, the broken line represents unclaimed environment only and forms no part of the claimed design.

1 Claim, 5 Drawing Sheets(56)
